UNITED STATES PATENT OFFICE.

CHARLES DEBREMONT, OF NEW ORLEANS, LOUISIANA, ASSIGNOR TO A. A. SMITHWICK, OF SAME PLACE.

DEVICE FOR HANDLING COINS.

SPECIFICATION forming part of Letters Patent No. 626,528, dated June 6, 1899.

Application filed March 24, 1898. Serial No. 675,024. (No model.)

To all whom it may concern:

Be it known that I, CHARLES DEBREMONT, a citizen of the Republic of France, residing at New Orleans, in the parish of Orleans and 5 State of Louisiana, have invented new and useful Improvements in Devices for Handling Coins, of which the following is a specification.

My invention contemplates the provision of a device adapted to automatically separate 10 coins, indicate the number of each denomination of coins on hand, enable a salesman or cashier to readily make change, and indicate the number of each denomination of coin ejected incident to the making of change, so 15 as to lessen the liability of mistake on the part of the salesman or cashier. It will be fully understood from the following description and claims when taken in conjunction with the annexed drawings, in which—

Figure 1 is a perspective view of a device embodying my invention. Fig. 2 is an enlarged section taken in the plane indicated by the line 2 2 of Fig. 6, with parts in elevation. Fig. 3 is a detail perspective view of the lower portion of one of the coin-holders. Fig. 4 is a similar view of one of the collars, in which the lower ends of the coin-holders are arranged and detachably secured. Fig. 5 is a perspective view of one of the coin-ejectors. Fig. 6 is a vertical central section of the device. Figs. 7 and 8 are detail sections taken in the planes indicated by the lines a a and b b, respectively, of Fig. 6. Fig. 9 is a section taken in the plane indicated by line 9 9 of Fig. 6. Fig. 10 is a detail section taken in the plane indicated by line 10 10 of Fig. 9. Fig. 11 is a top plan view, with some parts in section, illustrating the hopper in which the coins to be separated 40 are placed, together with the chutes connected with the hopper and leading to the coin-holder tubes; and Figs. 12 and 13 are sections taken in the planes indicated by the lines 12 12 and 13 13, respectively, of Fig. 11. In the said drawings similar letters designate corresponding parts in all of the several views, referring to which—

A designates the box or casing of the device, which may be of any construction and 50 ornamental design suitable to the purpose of my invention.

B designates six (more or less) metallic collars of different diameters, which are suitably connected to the top wall of casing A, around openings a therein, and are provided with inwardly-directed studs b and opposite depending portions b², and C designates the coin holders or tubes, each of which is of a diameter corresponding to that of the particular denomination of coin which it is designed to receive. For instance, the tube C to the right (see Fig. 1) is of a size to snugly receive dimes and that to the left of a size to snugly receive dollars, while the intermediate tubes are of sizes to enable them to snugly receive cents, 65 nickels, quarters, and half-dollars, respectively. Apart from differences in diameter and height the tubes C are similar in construction and are similarly connected with the casing A, and therefore a description of 70 the one shown in detail in Figs. 3, 4, 6, 7, and 8 will suffice for all. Said tube is preferably of glass, so as to enable the operator to see its contents, although it may be of any other suitable material, and it comprises lower 75 and upper sections c d, the lower section being arranged in collar B and being provided with a bayonet-slot e to receive the stud b, by which it is detachably connected to the collar, so as to permit of it being readily removed and discharged of its contents when desired. The lower and upper sections c d are provided with graduations numbered at suitable intervals to enable the operator to readily perceive the number of coins in the 85 tube. They are also preferably provided with coincident longitudinal slots, although said slots are not necessary except when the tube is formed of some opaque material. The said sections are connected together by a collar f, which surrounds and is cemented or otherwise connected to their contiguous ends, as best shown in Fig. 6. Said collar f is provided with a slot g for the reception of a valve or gate h and is also provided with a slotted 90 extension i, in which is arranged and adapted to move the handle j of the valve or gate. The valve or gate is normally held in a closed position by a coiled spring k, whereby it will be seen that when coins are discharged into 100 the upper end of the section d they will be supported by the valve or gate and will be

prevented from dropping into the lower portion of the tube. This enables the operator to see at a glance how many coins are deposited in the tube, when a mass of coins of 5 different denominations to be separated are placed in the hopper, (presently described,) and after noting the amount he has but to draw the valve or gate outwardly in order to cause the said coins to drop into the lower 10 portion of the tube.

The tubular coin-holders C are preferably formed of glass and in two sections, as has just been described. I desire it understood, however, that when formed of metal they may 15 be each formed in one or more pieces, as preferred.

D designates an upright which is connected to and rises from the casing A and is preferably provided with a shoulder l at an intermediate point of its height.

E designates a funnel-shaped hopper, which is designed to receive the mass of coins of different denominations to be separated, and F designates a spiral conveyer, which is 25 detachably connected to and depends from the lower end of the hopper E and comprises six (more or less) chutes $n' n^2 n^3 n^4 n^5$, as best shown in Figs. 11 to 13.

The conveyer F is designed to receive coins 30 from the hopper E, and in order to insure the said coins entering the conveyer in a flat-wise position the hopper is provided with an inclined wall G, upon which the coins fall and from whence they pass to the inclined 35 bottom wall p of the hopper, which leads to to the mouth of the conveyer. Each of the chutes comprised in the conveyer F terminates at its lower end in a spout q, which has a depending flange q', designed to take into 40 a collar-flange at the upper end of one of the coin-holding tubes C. Each chute, with the exception of the lower one, is also provided with openings r, those of the upper chute being too small for the passage of dollars, 45 but large enough for the passage of half-dollars and smaller coins, those of the next lower chute being too small for the passage of half-dollars, but large enough for the passage of quarter-dollars and smaller pieces, 50 those of the next lower chute being too small for the passage of quarter-dollars, but large enough for the passage of nickels and smaller pieces, those of the next lower chute being too small for the passage of nickels, but large 55 enough for the passage of smaller pieces, and those of the next lower chute being too small for the passage of pennies, but large enough for the passage of dimes. In virtue of this construction when a mass of coins is placed 60 in the hopper F the coins will be separated, as follows, viz: The dollar-pieces will remain on and slide down chute n, the half-dollars will drop from chute n to the chute n' and slide down said chute n', the quarter-dollars 65 will drop through chutes $n' n^2$ and slide down chute n^2 , the nickels will drop through chutes

$n' n^2$ and slide down chute n^3 , the pennies will drop through chutes $n' n^2 n^3$ and slide down chute n^4 , and the dimes will drop through chutes $n' n^2 n^3 n^4$ and slide down chute n^5 . 70 From the chutes the coins will pass into the respective spouts thereof and from thence into the tubular receptacles or holders with which the spouts communicate, as before described. The openings r in the chutes are, as best shown 75 in Fig. 11, arranged as near as possible to the outer wall of the conveyer, so that they will be in the path of the coins when the same are thrown outwardly by the centrifugal action incident to their downward course. 80

H designates a sleeve which is suitably connected with the conveyer F. This sleeve H is designed to take over the upper end of the upright D and bear on the shoulder l thereof, so as to support the conveyer F and the hopper E and their appurtenances, and in order to prevent an unauthorized person from lifting the hopper and the conveyer I contemplate connecting the sleeve H and upright D by a suitable lock s, as shown in Fig. 6. As 85 the tubes C cannot be lifted and discharged of their contents, as before described, until the ends of the spouts q are raised and swung away from their position above the tubes, it follows that the back connection between the 90 tube H and upright D will prevent an unauthorized person from lifting and discharging the tubes C of their contents.

Arranged in the casing A immediately below the opposite depending portions b^2 of the 95 collars B is a fixed horizontal plate I. This plate I is designed to support the slidable coin-ejectors J, of which six are employed, and is provided with slots t, receiving the depending portions u of the ejectors, so as to 100 guide the same in their movements.

The ejectors J are arranged in alignment with the spaces between the depending portions b^2 of the collars B and are provided at their inner ends with enlargements v, adapted when they are forced inwardly to engage the lowermost coins in the tubular holders, which rest on the plate I, and force said coins off the said plate and cause them to fall into the discharge-chute K, presently described. 110 At or adjacent to their outer ends the ejectors J are connected to one end of bell-crank levers w, the opposite ends of which are connected to finger-levers x, which extend through slots z in the front casing-wall, and are provided at their outer ends with buttons a', bearing appropriate inscriptions, as best shown in Fig. 9. When any one of these finger-levers is depressed, the ejector with which it is connected will be caused to move inwardly, so as 115 to displace a coin, and when pressure is removed from said lever it, together with the bell-crank lever and the ejector, will be returned to the position shown in Fig. 6 by a spring b', interposed between and connected 120 to the ejector and finger-lever, as shown.

When displaced from the plate I, the coins,

as before described, pass down the chute K. This chute K is designed to carry the coins to a cup or receptacle L at the front of the device, from whence they may be readily removed by the party entitled to the change.

It is sometimes desirable that the change should be delivered to the cashier or salesman operating the device. In order that this may be done when desired, I provide the chute M, which is pitched downwardly toward the back of the device and the normally-closed spring-pressed valve or gate N, which controls communication between the cup L and the upper end of said chute. To the said valve or gate N is connected a push-rod P, which extends to the rear side of the device, so as to enable the salesman to open the valve or gate P prior to ejecting coins from the coin-holding tubes, so as to cause said coins to pass down the chute M and be delivered to him at the rear side of the device. When the valve or gate is left in its normal position, it is obvious that the ejected coins will remain in the cup or receptacle L, from whence they may be readily removed by the person entitled to them.

For the purpose of sounding an alarm when a coin is ejected from any one of the coin-holding tubes I provide the alarm mechanism better shown in Figs. 2 and 6. This mechanism comprises a gong c', a rock-shaft d', which is provided with a hammer e', and also with upwardly-extending fingers f' and a coiled spring g', which is connected to the rock-shaft and the casing, as best shown in Fig. 2. The fingers f' of the rock-shaft are normally held in the path of the depending portions u of the ejectors J. Consequently it will be seen that when any one of the ejectors is moved inwardly, as is necessary to eject a coin, it will engage one of the fingers f' and rock the shaft d' in a direction to carry the hammer e' away from the gong c', and that when the ejector is quickly returned to its normal position by spring b' and the rock-shaft d' is released the hammer e' will by reason of the expansion of spring h' be forcibly carried against the gong c' and the alarm will be sounded.

In order to lessen the liability of mistake on the part of the salesman or cashier in making change, I have provided the mechanism shown in Figs. 2, 6, 9, and 10 for indicating the number of each denomination of coins ejected incident to the making of change. This mechanism comprises a fixed shaft h', six ratchet-wheels i', loosely mounted on the shaft and having twenty-four (more or less) teeth, and also having peripheral flanges j', bearing twenty-four numerals more or less arranged in consecutive order, spring-dogs k', fixed to the ejectors and adapted to engage the teeth of the ratchet-wheels and move the same the distance of one tooth at each inward movement of the ejectors, spring-pressed detents l', adapted to engage the teeth of the ratchet-wheels i' and prevent retrograde

movement thereof, coiled springs m', nested within the peripheral flanges j' of the ratchet-wheels and connected to said flanges and the shaft h', and a lock-shaft p'. The said shaft p' is provided with arms q' for engaging the angular arms q' of the detents l' and the lugs r' on the ejectors, as best shown in Fig. 10. It is also provided at one end with a handle s' and a spring t' for normally holding it in 75 and returning it to the position illustrated. It will be perceived that when in such position the shaft p' will prevent the operation of the ejectors J, and when it is fixed in such position by a lock (not shown) or any other suitable means the ejectors cannot be actuated, and in consequence coins cannot be removed from the device.

When it is desired to operate the device, it is simply necessary for the operator to depress the handle s' of the shaft p' with one hand and press the finger-levers x with the fingers of the other hand. The rocking of the shaft p' incident to the depression of the handle s' will release the ejectors J and the 90 detents l', and in consequence the ejectors will be free to move inwardly to eject coins, and the mechanism for indicating the number of each denomination of coins will be rendered operative. The operation of such indicating mechanism is as follows: When any one of the finger-levers x—the dollar-lever, for instance—is depressed, the ejector connected with said lever will be moved inwardly and will eject the lowermost dollar in 100 the dollar-tube C. At the same time the dog k' on the ejector will engage the ratchet-wheel i' and rotate the said wheel the distance of one tooth. With this done the numeral "1" on the flange j' of the ratchet-wheel will appear opposite the opening u' in the casing, which is arranged in alinement with the dollar-tube C and dollar-lever x and will indicate that one dollar has been ejected. The 105 detent-lever l' will, as stated, prevent retrograde movement of the ratchet-wheel i', and as the said wheel is rotated the distance of one tooth at each inward movement of the ejector a number corresponding to the number of coins ejected will appear opposite the 110 opening u'. The several detents l' are adapted to prevent retrograde movement of the ratchet-wheels i' so long as the handle s' of shaft p' is depressed, and consequently the operator after striking one or more of the finger-levers x to make change is enabled by 115 looking at the flanges j' of the ratchet-wheels i' through the openings u' to see the number and denomination of the coins ejected and satisfy himself that the correct amount of 120 change has been given. When pressure is removed from the handle s', the rock-shaft p' and its appurtenances will by reason of the spring t' be returned to the position shown in Fig. 10, and in consequence the ejectors will 125 be locked against movement and the detents l' will be disengaged from the ratchet-wheels 130

7. When the detents are thus disengaged, the ratchet-wheels and of course their flanges will by reason of the springs *m* be moved backwardly, so that the figure "0" will appear 5 opposite all of the openings *u*.

In the practice of my invention it is obvious that the device may be constructed so as to adapt it to receive and handle the coins of any country. It is also obvious that many 10 changes in the construction and relative arrangement of the parts of my improved device may be made in practice without departing from the spirit of my invention.

Having thus described my invention, what 15 I claim is—

1. In a device for separating coins, the combination of a suitable base, an upright connected to and rising therefrom and having a shoulder, a plurality of coin-holding tubes 20 mounted upon the base and detachably connected thereto; a hopper arranged in a plane above the coin-holding tubes, a plurality of chutes disposed one above the other and arranged to receive from the hopper and terminating 25 at their lower ends in spouts bearing upon and adapted to discharge into the upper ends of the coin-holding tubes; a sleeve connected with the hopper and chutes and arranged upon the upper end of the upright 30 and bearing on the shoulder thereof; and a suitable lock connecting said sleeve and the upright, substantially as specified.

2. In a coin-handling device, the combination of a base, a collar connected thereto and having opposite depending portions, a coin-ejector movable between the said depending portions of the collar, a coin-holding tube arranged in and detachably connected to the collar, a hopper disposed above the base and 40 detachably connected with the same, and an inclined closed conveyer connected at its upper end to the hopper and terminating at its lower end in a closed spout having a depending flange engaging the upper end of the coin 45 holder, substantially as specified.

3. In a device of the class described, the combination of a base, a coin-holding tube mounted on said base, a slidable ejector for displacing the lowermost coin from the tube, 50 a bell-crank lever connected at one end to said ejector, a finger-lever fulcrumed at one end and connected at an intermediate point of its length to the other end of the bell-crank lever, a cup or receptacle arranged at the 55 front of the casing, a chute adapted to receive coins when they are ejected from the tube and conduct the same to the cup or receptacle, a chute extending downwardly from the cup or receptacle to the rear of the casing, 60 and a valve or gate interposed between the cup or receptacle and said chute, substantially as specified.

4. In a device of the class described, the combination of a casing containing a base- 65 plate, a coin-holding tube mounted on said base-plate, an ejector for displacing the low-

ermost coin from the tube, a cup or receptacle arranged at the front of the casing, a chute adapted to receive coins when they are ejected from the tube and conduct the same to the cup or receptacle, a chute extending downwardly from the cup or receptacle to the rear of the casing, and a valve or gate interposed between the cup or receptacle and said chute, substantially as and for the purpose set forth. 70 75

5. A device of the class described comprising a suitable casing, a coin-holder, means for ejecting coins from the holder, a cup or receptacle arranged at the front of the casing, a chute adapted to receive coins when they are ejected from the holder and conduct the same to the cup or receptacle, a chute extending downwardly from the cup or receptacle to the rear of the casing, a spring-pressed valve or gate interposed between the cup or 80 receptacle and said chute, and a push-rod connected with said valve or gate, substantially as specified.

6. A device of the class described comprising a plurality of coin-holders, independent 90 ejectors for displacing the lowermost coins from the holders, a gong, means operative by the ejectors for striking the gong, and a spring-pressed lock-bar having arms normally engaging and adapted to hold the ejectors 95 against movement and also having a handle, substantially as specified.

7. A device of the class described comprising a casing, a gong, a plurality of coin-holders, independent ejectors for displacing the 100 lowermost coins from the holders, a rock-shaft having a hammer and also having fingers, a spring connected to said shaft for normally holding the fingers of the same in the path of the ejectors, and a spring-pressed lock-bar 105 having arms normally engaging and adapted to hold the ejectors against movement and also having a handle, substantially as specified.

8. A device of the class described comprising a plurality of coin-holders, ejectors adapted when moved to remove coins from the holders, and a spring-pressed lock-bar having arms normally engaging and adapted to hold the ejectors against movement and also having a handle, substantially as specified. 110 115

9. A device of the class described comprising a casing having an opening *u*, a coin-holder, a coin-ejector carrying a dog, a shaft, a ratchet-wheel loosely mounted on the shaft 120 in the path of the dog on the ejector and having a portion bearing numerals on its periphery, a spring connected with the shaft and ratchet-wheel, and a detent for preventing retrograde movement of the ratchet-wheel, 125 substantially as specified.

10. A device of the class described comprising a casing having openings *u*, a plurality of coin-holders, a plurality of independently movable coin-ejectors provided with dogs, a 130 shaft, ratchet-wheels loosely mounted on said shaft in the paths of the dogs on the ejectors

and having portions bearing numerals on their periphery, coiled springs connected with the shafts and ratchet-wheels, spring-pressed detents for preventing retrograde movement of the ratchet-wheels, and a spring-pressed locking-bar for normally holding the detents out of engagement with the ratchet-wheels, substantially as specified.

In testimony whereof I have hereunto set my hand in presence of two subscribing witnesses.

CHARLES DEBREMONT.
